MINIATURE RACING CAR

Samuel R. Bergman, Los Angeles, Calif., assignor to Classic Industries, Inc., a corporation of California

Filed May 27, 1965, Ser. No. 85,482

Term of patent 7 years

(Cl. D34—15)

Fig. 1

Fig. 2

Fig. 3

Fig. 4

FIG. 1 is a top plan view of a miniature racing car showing my new design;

FIG. 2 is a side elevational view;

FIG. 3 is a rear elevational view; and

FIG. 4 is a front elevational view.

I claim:

The ornamental design for a miniature racing car, as shown.
